ATTORNEY

UNITED STATES PATENT OFFICE

CARL A. LIND, OF MARATHON, IOWA

BOX COVER FASTENER

Application filed May 31, 1930. Serial No. 458,234.

This invention relates to certain new and useful improvements in fasteners of a type designed for securing the lids of egg cases or crates.

5 One of the principal objects of the invention consists of a means of anchorage for the fasteners being disposed in such manner to serve the added purpose of wear plates and to obviate flaring of the secured ends 10 of the lid proper.

Another object of the invention resides in the provision and arrangement of fasteners of this character swingably supported upon the wear plates to occupy their 15 respective positions.

More specifically stated the fasteners are designed for yielding biting engagement with appropriate portions of the egg case or crate proper.

20 With the above and other objects in view, the invention further consists of the following novel features and details of construction, to be hereinafter more fully described, illustrated in the accompanying drawings 25 and pointed out in the appended claims.

In the drawings:

Figure 1 is a side elevation of a form of egg case or crate with the invention applied and in use.

30 Figures 2 and 3 are fragmentary end elevations of the case showing by full and dotted lines the respective positions of the fasteners when shifted for active use.

Figure 4 is a fragmentary top plan view 35 of the egg case showing the particular disposition of the wear plate.

Figure 5 is a sectional view taken on line 5—5 of Figure 4.

40 Figure 6 is a detail perspective view of the fastener.

Referring to the drawings in detail wherein like characters of reference denote corresponding parts, the reference character 10 indicates generally a form of egg case or 45 crate having a closure lid 11 projecting at its ends outwardly beyond the extremities of the crate and reposing upon the upper surfaces of cleats 12 generally employed for the purpose of accommodating the shanks of 50 forms of fastenings, not shown, usually

passed through the overlapping extremities of said lid. It is my purpose to employ the present invention upon a crate or case of this character and to preserve the overlapping relation of the extended ends of the 55 closure lid and the cleats 12. This is accomplished through the provision and arrangement of wear plates 13 of angular formation, that is, the respective faces thereof 60 repose against the upper side of the lid and the outer surface and ends of said lid, substantially as illustrated in Figures 1 and 5 of the drawings. Barbs or penetrating elements 14, carried by and struck from those faces 65 of the wear plates 13 reposing upon the upper surface of the closure lid 11, are embedded within the latter in the manner suggested in Figure 5 of the drawings whereby the wear plates and closure lid are to be removed and replaced as a unit. 70

The fasteners 15 are to be constructed from lengths of spring wire formed with attaching loops 16 swingably supported within sleeves 17 arranged upon the outer depending sides 75 of the angular forms of wear plates.

The body portions of the fasteners have the ends 18 therefor extended from the attaching loops 16 and offset, as at 19, to underlie the cleats 12 in the manner shown in Figure 5 whereby the pointed extremities 20 of said offsets may be embedded for appreciable portions of their lengths within said cleats. Open loops 21 forming the means of connection between the attaching loops 16 and the longer ends of the fasteners are frictionally engaged with the shorter ends 18 to obviate fulcrums from which the longer ends of the fasteners may be swung. The extremities of the longer ends of the fasteners are also successively offset as at 22 and 23 respectively after the manner of the ends 18. It is to be noted that the spring tension of the fasteners themselves and the biting engagement of the extremities thereof with the under surfaces of the cleats 12 provide the means for securing the fasteners in position for use and against accidental displacement. It is to be noted that the fasteners may be arranged in any size and number upon the wear plates 13 and as suggested in Figure 3 of the 100

drawings two of the fasteners may be arranged adjacent the ends of one of the wear plates whereby a solitary fastener may be arranged adjacent the middle of the other oppositely disposed wear plate. It is obviously apparent from the respective positions of the fasteners shown in Figures 2 and 3 of the drawings just how the fasteners are lockingly engaged and released with relation to the 10 cleats.

The invention is susceptible of various changes in its form, proportions and minor details of construction, and the right is herein reserved to make such changes as properly 15 fall within the scope of the appended claims.

Having described the invention, what is claimed is:

1. A box fastener comprising wear plates of angular formation arranged adjacent to 20 and overlying the ends of the lid therefor, fastening elements swingably supported upon the wear plates beyond the ends of the lid and out of alignment with the outer surface the latter, and the ends of the fasteners 25 being shaped for biting engagement with the box.

2. A fastener for lids upon boxes of a type having cleats arranged upon the outer sides of the end walls therefor to seat the lid thereon, wear plates of cross section angular formation carried upon the ends of the lid having portions overlying the outer sides of the cleats, sleeves formed at intervals upon the corner portions of the wear plates, fastening 30 elements having attaching loops formed at points eccentrically thereof swingably supported from said sleeves, and the ends of the fastening elements being offset and provided with pointed extremities for biting engagement with those portions of the cleats in oppositely disposed relation to the connections of the lid therewith.

In testimony whereof I affix my signature.
CARL A. LIND.
